UNITED STATES PATENT OFFICE

JACK KUGELMAN, OF PHILADELPHIA, PENNSYLVANIA

DESIGN FOR A STOCKING

Application filed December 17, 1931. Serial No. 42,116. Term of patent 3½ years.

To all whom it may concern:

Be it known that I, JACK KUGELMAN, a citizen of the United States, and residing at Philadelphia, county of Philadelphia, and State of Pennsylvania, have invented a new, original, and ornamental Design for Stockings, of which the following is a specification, reference being had to the accompanying drawings, forming part thereof.

I claim:

The ornamental design for a stocking as shown and described.

JACK KUGELMAN.
